UNITED STATES PATENT OFFICE.

EDWIN W. LODGE, OF NORFOLK, VIRGINIA, ASSIGNOR OF ONE-FOURTH TO FREDERICK D. COCK, OF HAMPTON, VIRGINIA.

RECEPTACLE.

Application filed October 7, 1921. Serial No. 506,068.

To all whom it may concern:

Be it known that I, EDWIN W. LODGE, a citizen of the United States, residing at Norfolk, in the county of Norfolk and State of

5 Virginia, have invented certain new and useful Improvements in Receptacles, of which the following is a specification.

My invention relates to receptacles.

The object of the invention is to provide 10 a receptacle for ice cream, oysters and other food products which may have the form of a cylindrical box and be transformed into a saucer from which food may be eaten.

Further objects and advantages will be 15 more fully described herein and specifically pointed out in the claims hereunto annexed, recourse being had to the accompanying drawing forming a part of this specification in which:

20 Figure 1 is a plan of my invention when flattened out.

Figure 2 is an elevation of the receptacle when formed into a box, and

25 Figure 3 is a side view of the receptacle when transformed into a saucer or dish.

In the drawing like reference numerals indicate similar parts in all the several views.

My invention is formed from a blank or 30 circular disc of paper, cardboard or similar material, suitably waxed or otherwise rendered waterproof and crimped or folded from the bottom circle 1 to the periphery, starting at points 1^a, increasing in width as the folds leave the centre or bottom 1.

35 The starting point of the folds, as at 1^a, are at a slight tangent to the circle 1 and may be of any number as 12, as shown on the drawing.

The crimped or folded portions have wide 40 parts 2 and narrow surfaces 3 and when my

device is compressed by the hand to form a cylindrical box, as in Figure 2, the folds overlap each other as shown.

When the receptacle is used as a box as in Figure 2, it is dipped in melted wax, 45 paraffin or some adhesive substance and upon cooling suffices to hold the folds 2 and 3 together in any position and, when the box is to be used as a saucer, it is forcibly spread towards a flattened position, as shown in 50 Figure 3.

When the receptacle is used as a box, the top 4 is applied when the same is filled with its contents, and holds the folds in contact with each other in addition to the adhesive 55 dip, by covering the edge 5.

The receptacles are made slightly tapering, as in Figure 2, to permit them to be nested for packing and transportation.

My invention can be made in any size as 60 desired and is both cheap and effective besides providing a handy carrier for many uses.

I claim:

A receptacle formed of a single piece of 65 paper, said paper adapted to be unequally and tangentially creased from a given central circular space to the outer edge of the blank to form a cylindrical container and of sufficient stiffness to adapt same to be formed 70 into a flattened position, and cover means for holding the folds when in a cylindrical form.

In testimony whereof I have hereunto affixed my signature in the presence of two 75 witnesses.

EDWIN W. LODGE.
